UNITED STATES PATENT OFFICE.

WILLIAM VAUGHN, JR., OF PASSAIC, NEW JERSEY, ASSIGNOR OF ONE HALF
TO WILLIAM LAYTHAM, OF SAME PLACE.

DESIGN FOR A STEPPING-BLOCK.

SPECIFICATION forming part of Design No. 24,370, dated June 4, 1895.

Application filed October 18, 1894. Serial No. 526,320. Term of patent 7 years.

To all whom it may concern:

Be it known that I, WILLIAM VAUGHN, Jr., a citizen of the United States, residing at Passaic, in the county of Passaic and State of New Jersey, have invented and produced a new and original Design for a Stepping-Block; and I do declare the following to be a full, clear, and exact description of the same, reference being had to the accompanying drawing, showing a perspective view thereof.

My invention relates to designs for ornamental stepping blocks and it consists in its leading or characteristic features of a rectangular block, provided with an outwardly flaring ornamental base, diamond-figured top and paneled sides, having the representation of columns duplicated on its corners, as shown.

A is the top of the block, ornamented with

a diamond-figured pattern with upwardly protruding points. B is a panel with half round beads on its outer edge. C is ornamental raised work within the side panels; D, half round ornamental columns duplicated on the corners, the whole surmounting an outwardly flaring base provided with suitable moldings, as shown.

Having thus described my invention, what I claim is—

The design for a stepping block, as herein shown and described.

In testimony whereof I affix my signature in presence of two witnesses.

WILLIAM VAUGHN, JR.
